FABRIC SIMULTANEOUSLY WITH THE
WEAVING OF THE FABRIC

Franz C. Mostertz, Philadelphia, Pa.

Application March 1, 1951, Serial No. 213,434

16 Claims. (Cl. 139—11)

1
This invention has reference to the production of slide fasteners, and more particularly those of the type in which the stringers are each composed of a continuous, spirally-arranged element. Each of the stringers is secured in a tape and the present invention contemplates the weaving of a tape in which the stringers are incorporated during the weaving operation.

In weaving a spiral fastener stringer of this character into a tape, it is important that the use of tension or pull on the stringer be minimized since the imposition of tension on the spiral stringer has a tendency to pull and distort the spiral. When this occurs the spiral is often distorted or stretched to such an extent as to produce a different number of convolutions per inch of tape than the amount intended, resulting in the failure of proper engagement between opposing stringers. It is, therefore, an object of the invention to provide means for feeding the spiral in a manner which will prevent stretching or twisting of the spiral, thus insuring the presentation of the spiral to the weaving operation in an undistorted manner and resulting in the spiral being attached to the tape in straight-line formation and with the proper number of convolutions to each inch of tape.

Another object of the invention is to provide means by which each of the filling or weft threads is held as it is passed through the spiral, thus preventing inadvertent withdrawal of such threads on return shuttle movements. Still another object is to provide a novel feeding means for the spiral, and means by which the woven tape, with the spiral incorporated in the same, will be held flatly and prevented from twisting as the same proceeds to the take-up reel.

These and other objects to be set forth are attained by the invention, a more particular description of which will hereinafter appear and be set forth in the claims appended hereto.

In the accompanying drawings, wherein an illustrative embodiment of the invention is disclosed,

Fig. 1 is a schematic view of a loom mechanism constructed according to the invention;

Fig. 2 is a side elevational view of the operating mechanism for the feeding of the spiral fastener stringer and for operation of the weft-retaining finger;

Fig. 3 is a top plan view of the mechanism of Fig. 2, with parts broken away to disclose construction;

Fig. 4 is a top plan view showing portions of the batten, shuttle, weft-retaining finger, tape-engaging rollers and associated elements;

2
Fig. 5 is a sectional view taken on the line 5—5 of Fig. 4, looking in the direction of the arrows.

Fig. 6 is a cross sectional view through the spiral element and the tube through which it is fed; the section being taken on the line 6—6 of Fig. 2, looking in the direction of the arrows;

Figs. 7 and 8 are diagrammatic views showing the action of the weft-retaining finger, and

10 Fig. 9 is a sectional view through a portion of the tape with the spiral stringer secured thereto.

The improved mechanism herein disclosed has reference to the production of a fabric tape which has, adjacent to one of its longitudinal edges, a spiral stringer of the character used for slide fasteners.

By reference to Fig. 9 wherein a cross section of the tape and attached fastener is seen, it will be therein noted that the warp threads are indicated at 10 and the weft threads at 11. A heavier warp thread, adjacent to the spiral stringer 12, is shown at 13, and it will be observed that an edge portion 14 of the tape extends from said warp thread 13 to partly overlap or partly cover the spiral stringer 12.

In the production of such a tape and spiral-stringer combination, the warp threads from which the tape is woven are contained upon the supply reels generally indicated at 15 in Fig. 1. Said threads, indicated at 16 and 17 in Fig. 30 1, extend from the reels 15 over several tension rods 18 and through the heddles 19 in the conventional manner, then passing through the reed 21 carried by the batten 20. The shuttle 22 is mounted for reciprocating and arcuate movement, on the batten 20. These elements thus far described, are conventional in certain types of looms.

The spiral fastener stringer 12 which is adapted to be inserted in the tape by the weaving operation is seen in cross section in Fig. 6. The stringer is continuously fed from a reel or coil indicated at 23 and the same, when drawn from the reel 23 is passed under a guide or tension roll 24 and thence through a feeding device generally indicated at 25. Said feeding device, which is shown in detail in Fig. 2, includes a base member 26 fixedly mounted on or forming a part of the frame of the loom, and arising from said base member is a tubular housing 27. Extending transversely through the housing 27 near the upper end thereof is a guide sleeve or tube 28 which has a cross sectional shape corresponding to that of the spiral stringer 55 12, as shown in Fig. 6, thereby preventing twist-

ing or rotative movement of the stringer within the guide sleeve or tube 28. The spiral stringer 12 is fed through the sleeve or tube 28 by means of a worm gear 29 located in the housing 27 above the sleeve or tube 28 and engaging with the convolutions of the stringer through an aperture 30 in the tube 28. The worm gear 29 has its teeth corresponding exactly to the convolutions of the spiral stringer.

The worm gear 29 is mounted upon a rotatable shaft 31, rotative in suitable bearings in the shaft 31, and the shaft 31 carries a sprocket 32 receiving the chain 33 which extends downwardly through the housing 27 and adjacent to the lower end of the housing extends about a sprocket 34 on a shaft 35 rotative in the housing. Said shaft carries, externally of the housing, a sprocket 36 which receives a chain 37 that extends about a sprocket 38 on a shaft 39 rotative in a bearing 30a at the upper end of an upright member or post 31a secured to and rising from the base 26. Carried on the shaft 39 is a bevel gear 40 which meshes with a bevel gear 41 on gear 40 which meshes with a pinion 47 on a shaft 48 extending parallel to the shaft 42. On the lower end of the vertical shaft 42, below the base member 26, is a worm gear 43 in mesh with a worm 44 on a shaft 45 extending transversely of the base 26, and said shaft 45 carries a gear 46 in mesh with a pinion 47 on a shaft 48 extending parallel to the shaft 42. Also secured on the shaft 48 is a sprocket 49, engaged by the chain 50 which extends about a sprocket 51 on the main shaft 52 of the machine. The main shaft 52 is rotated at the proper speed by a motor or other power source. An idle sprocket 53 rotatively carried at the end of the arm 54 takes up the slack in the chain 50.

The arrangement above described is such as to cause the spiral stringer to be fed at a speed to provide a given number of convolutions in the stringer to the inch of tape. After passing through the guide sleeve or tube 28, the spiral stringer is fed through a guide tube 55 which also corresponds in cross-sectional shape to the contour of the spiral stringer. Adjacent to its entrance end 56, the tube is attached to a head 57 mounted for rocking movement in a tubular rod 58 secured to the harness frame 59. This arrangement is such that when the harness frame is vertically reciprocated during the usual weaving operation, the tube 55 will be moved with it.

The shuttle 22 which lays the weft threads in position is movable on a curve or arc as is known in certain types of looms in use today, and as the weft threads are laid in place, with the spiral stringer 12 extending co-extensive with the warp threads and being engaged by the weft threads in similar manner, it is desirable that when each weft thread is laid in position and enters between the convolution of the spiral stringer, such thread be prevented from rising out of the stringer on the return movement of the shuttle. The manner in which this is accomplished is illustrated in Figs. 4, 7 and 8. In Fig. 7 a weft thread indicated at 60 is being laid in place by movement of the shuttle in the direction of the arrow or toward the stringer 12. In Fig. 8 the weft thread has been laid in place and the shuttle is on its return movement in a direction away from the stringer. Since the shuttle describes a trajectory it has a tendency to pull the weft thread through such trajectory and the normal result would be to pull the weft thread out of the convolutions of the spiral.

Hence it is desirable to provide a thread-retaining finger indicated at 62.

In Fig. 7 the finger 62 is shown in its retracted position, or is located rearwardly of the shed, so that it is out of the way of the shuttle. In Fig. 8 the finger 62 has been advanced to its retaining position and is engaging the weft thread which has just been laid in place, the finger acting to hold the thread just beyond the spiral and preventing it from being pulled up out of the convolutions thereof.

The mechanism for operating the finger 62 is shown in Figs. 4 and 5, wherein it will be noted that the finger is provided with a forward, downwardly-bent end 63 for engagement with the threads as just described, the finger being adjustable as to effective length in a rear sleeve portion 64, pivoted at 65 to a link 66 secured on a rocking shaft 67 rotative in a bracket 68. Said shaft 67 is oscillated by means of linkage which includes an arm 69 secured at one end to shaft 67 and having its other end pivotally attached at 70 to a link 71 having its lower end pivotally attached at 72 to the upper end of a lever 73. The lower end of the lever 73 is pivoted at 74 between lugs 75 secured to a frame member 76.

The sleeve portion 64 of the finger 62 is slidable through a boss 77 which is rotatively mounted in the bracket 68, this arrangement being such as to cause the free end 63 of the finger to be elevated by rotational movement of the boss 77 when the finger is drawn to its retracted position, or that shown in dotted lines in Fig. 5. A link 79 has one end pivotally connected at 80 to the lever 73, the opposite end of said link being pivotally connected at 81 to a lever 82. Said lever 82 has its upper end pivoted at 83 in a bracket 84 mounted on the supporting post or standard 85. Lever 82 carries a cam roller 86 operative against the edge of a cam 87 mounted on shaft 88, which shaft carries a gear 89. Meshing with the gear 89 is a pinion 90 located on the shaft 91 which carries a sprocket 92, engaged by the chain 93 extending about a sprocket 94 on the main shaft 52 of the loom. A spring 100 extending between the lever 73 and a lug 111 on the frame member 76 acts to hold the cam roller 86 in constant contact with the cam 87.

It will be apparent that by means of the mechanism just described, and which is properly timed for cooperation with the other parts of the apparatus, that the finger 62 will be moved forwardly and downwardly to engage and hold the weft thread when it is laid through the convolutions of the spiral stringer, and then be elevated and retracted as the batten is brought forward to pack in the thread.

To hold the woven tape and the spiral stringer anchored therein flatly and prevent the same from twisting or spiralling, I provide a pair of rollers indicated respectively at 95 and 96. It will be noted that these rollers are each grooved as indicated at 97 to conform to the contour of the spiral stringer. The upper roller 95 is rotatively mounted in a clevis 98 pivoted at 99 between the arms of a yoke 100 that is hinged at 101 to a part of the bracket 68. The pressure imposed by the rollers on the tape is regulated by a spring 102 surrounding an adjusting screw 103 threaded through the clevis 98 and operative against a part of the yoke 100.

From the foregoing, the operation of the improved structure will be readily understood. The warp threads 16 and 17 fed from the reels or spools 15 pass through the heddles and batten in

the conventional manner. The spiral stringer is fed from the supply reel 23 and passes through the guide sleeve 28 where it is engaged by the worm gear 29 and is fed thereby at the proper rate of feed through the guide sleeve 28. The spiral stringer after issuing from sleeve 28 then passes through the tube 55 and through the batten to reach the shed where it is engaged by the weft threads as the same are laid in place by movements of the shuttle. As each weft thread is laid in position by the shuttle movement toward the spiral stringer, such thread is momentarily engaged and held by the retaining finger 62. The finger then retracts to be out of the way of the batten as the same moves to pack in the weft threads.

After the tape is woven and with the spiral stringer in place, the same passes between the rollers 95 and 96 which hold the tape and spiral stringer against twisting movement, and the tape is then wound up on the reel indicated at 105. In carrying out the invention, the employment of tension upon the spiral stringer is avoided and the result is that a uniformity of stringer convolutions to each inch of the tape ensues and a smoothly-operating fastener is the result.

Having described one embodiment of the invention, it is obvious that the same is not to be restricted thereto, but is broad enough to cover all structures coming within the scope of the annexed claims.

What I claim is:

1. An apparatus of the character described comprising, a loom for weaving a tape and including means for moving warp threads to a shed, a spiral fastener stringer moved co-extensively with the warp threads to the shed, means for moving said spiral stringer comprising a guide sleeve provided with an aperture, and a rotative toothed element operative through said aperture and engaging the convolutions of the spiral stringer to move said spiral stringer axially toward the shed of the tape in which it is woven.

2. In a loom by which a spiral fastener stringer is woven into a tape, means for feeding the spiral stringer comprising a rotative element engaging the spiral convolutions of the stringer and moving the same toward the point at which it is woven into the tape.

3. In a loom for weaving a spiral fastener stringer into a tape, feeding means for the spiral stringer comprising, a sleeve conforming in cross-sectional shape to the contour of the stringer and through which the stringer is moved, said sleeve having an aperture in its side wall, a rotated worm gear mounted adjacent to the sleeve and having its peripheral edge entering through the aperture to engage with the convolutions of the spiral stringer passing through the sleeve to thereby move the stringer through the sleeve by the rotation of said worm gear.

4. In a loom for weaving a spiral fastener stringer into a tape, a support having a sleeve through which the spiral fastener stringer is moved, said sleeve having an aperture, a worm gear extending through the aperture and in engagement with the convolutions of the spiral stringer to thereby feed the stringer by revolutions of the worm gear, a harness through which the stringer is fed, said harness carrying a tube through which the stringer passes, said tube being free at one end and pivotally attached to the harness at its other end.

5. In a loom by which a spiral fastener is woven into a tape, means for feeding the spiral stringer

toward the shed, said means comprising a rotative member having a peripheral edge engaging in the convolutions of the stringer and moving the stringer axially by rotation of said member, and guiding means through which the stringer is passed, said guiding means being of a shape to prevent twisting movement of the stringer and having an aperture through which the rotative member enters to engage the stringer.

6. In a loom by which a spiral fastener stringer is woven into a tape, means for feeding the spiral fastener stringer co-extensively with the warp threads which are incorporated in the tape, a batten carrying a shuttle by means of which weft threads are inserted in the tape and which weft threads engage the convolutions of the spiral stringer, and a movable finger operative to engage and hold each weft thread in position beyond the convolution of the spiral stringer in which it is placed, to thereby prevent lifting of said thread out of the convolution on return shuttle movement, and means by which said finger is moved to thread-engaging or thread dis-engaging position in relation to movements of the shuttle.

7. In a loom by which a spiral fastener stringer is woven into a tape, a supply reel from which the spiral stringer is removed, a guide sleeve through which the stringer is fed, a gear engaging the convolutions of the spiral stringer and feeding the stringer axially through the sleeve, a loom harness frame, a tube having an end pivotally connected in said harness frame, the spiral stringer being fed through the tube to the shed of the tape being woven, and means beyond the shed for holding the tape and stringer inserted therein against twisting, said means including a pair of rollers between which the tape is passed, said rollers being grooved to fit the confirmation of the spiral stringer held in the tape.

8. In a loom by which a spiral fastener stringer is woven into a tape, means for feeding the spiral fastener stringer co-extensively with the warp threads which are incorporated in the tape, a batten carrying a shuttle by means of which weft threads are inserted in the tape and which weft threads engage with the convolutions of the spiral stringer, a movable finger operative to engage and hold each weft thread in position beyond the convolution of the spiral stringer in which it is placed to thereby prevent lifting of said thread out of the convolution on return shuttle movement, means by which said finger is moved to thread-engaging or thread dis-engaging position and rollers between which the woven tape and contained stringer are held flatwise.

9. In a loom by which a spiral fastener stringer is woven into a tape, feeding means for the stringer including a support through which the stringer is fed, a gear for engaging the convolutions of the spiral stringer to thereby feed the same axially to weaving position, a loom harness through which the stringer is passed on its way to weaving position, said harness carrying a tube through which the fastener stringer passes, said tube having one end pivotally attached to the harness.

10. In a loom as provided for in claim 10, wherein the tube through which the stringer passes has an internal shape corresponding to the external shape of the stringer so that the stringer cannot rotate within the tube.

11. In a loom for weaving a spiral fastener stringer into a tape, a pair of guide tubes through which a continuous length of spiral fastener stringer is axially fed, a rotative gear at one of

the tubes for engaging the convolutions of the spiral fastener stringer and moving the fastener stringer axially toward and through the second tube and toward weaving position, the spiral stringer being of non-round shape, and the internal contour of both of the tubes corresponding in shape to the shape of the spiral stringer.

12. In a loom for weaving a spiral fastener stringer into a tape, means for feeding a plurality of warp threads to weaving position, means for feeding a spiral fastener stringer co-extensively with the warp threads, guiding means for the stringer, said guiding means including a pair of tubes of internal cross-sectional shape corresponding to the shape of the stringer, rotative feed means at one of the tubes for engaging the convolutions of the spiral stringer and feeding the stringer axially and through the second tube, the second tube having an end pivotally carried by the loom harness, a batten carrying a shuttle for laying in the weft threads, a movable finger for engaging each weft thread after being laid in a convolution of the spiral fastener and prevent displacement of said thread from the convolution, and rollers between which the woven tape with the incorporated stringer are passed, the rollers having edge grooves shaped to conform to the shape of the tape and stringer.

13. In a loom for weaving a spiral fastener stringer into a tape, a plurality of guide tubes through which a continuous length of spiral fastener stringer is axially fed, a rotative gear at one of the tubes for engaging the convolutions of the spiral fastener stringer and moving the fastener stringer axially toward a second tube and toward weaving position, the spiral stringer being of non-round shape, and the internal contour of the tubes corresponding in shape to the shape of the spiral stringer, one of the tubes being carried by the loom harness and being pivotally attached thereto.

14. In the method of weaving a spiral fastener stringer into a woven tape, the step of feeding the fastener stringer axially and co-extensively with the warp threads of the tape, and guiding the stringer through guideways of an internal contour similar to the external shape of the

stringer to thereby prevent twisting movement of the string while the same is being fed.

15. In the method of weaving a spiral fastener stringer into a woven tape, the steps of feeding the stringer co-extensively with the warp threads of the tape, in inserting weft threads across the warp and engaging each weft thread as it is laid and holding the same at a point on the outside of the inserted stringer to prevent the thread from displacement on shuttle return.

16. In a loom by which a spiral fastener stringer is woven into a tape, means for feeding the spiral fastener stringer co-extensively with the warp threads which are incorporated in the tape, a batten carrying a shuttle by means of which weft threads are inserted in the tape and which weft threads engage the convolutions of the spiral stringer, a movable finger operative to engage and hold each weft thread in position beyond the convolution of the spiral stringer in which it is placed to thereby prevent lifting of said thread out of the convolution on return shuttle movement, the finger being moved to thread-engaging or thread disengaging position in relation to movements of the shuttle, and means for operating said finger as described, consisting of a bracket, a swinging link pivoted thereon, means for causing swinging movement of the link, one end of the finger being pivoted to said link, a member mounted for oscillatory movement on the bracket, the finger being slidable through said oscillatory member, whereby a raising movement is imparted to the forward end of the finger as the finger is retracted from operative thread-engaging position.

FRANZ C. MOSTERTZ.
